DISPLAY BOX FOR A PEN, A PENCIL, OR THE LIKE

Carol Cobblewick, Mount Vernon, and Robert J. Harper, Scarsdale, N.Y., assignors to Scripto, Inc., a corporation of Georgia

Application October 10, 1957, Serial No. 48,053

Term of patent 14 years

(Cl. D80—5)

Fig. 6

Fig. 7

Fig. 1 is a perspective view of a display box for a pen, a pencil, or the like showing our new design;

Fig. 2 is a top plan view;

Fig. 3 is a bottom plan view thereof;

Fig. 4 is a front elevational view thereof;

Fig. 5 is a rear elevational view thereof;

Fig. 6 is a side elevational view thereof; and

Fig. 7 is a side elevational view thereof with the cover in an open position.

The essential features of our design reside in the portions shown in solid lines in the drawings.

We claim:

The ornamental design for a display box for a pen, a pencil, or the like, as shown and described.
